UNITED STATES PATENT OFFICE

2,676,482

WALL OF REINFORCED SPACED BUILDING BLOCKS

Howe E. Wilson, Washington, Ind.

Application January 2, 1951, Serial No. 203,845

3 Claims. (Cl. 72—44)

1

This invention comprises novel and useful improvements in a building block interconnector and more specifically pertains to a device for rigidly reinforcing building block used in the construction of a wall made up of several courses.

An object of this invention is to provide a building block interconnector which may be easily applied while building the wall and which will be manufactured, together with the building blocks, in a precise manner.

Another object of this invention is to provide a building block interconnector which is provided with a means for effectively resisting longitudinal separation of the building blocks, vertical separation of the blocks, and generally applied lateral force of the wall.

Still another object of this invention is to provide a reinforcing means for interlocking the building block of a wall construction which further provides a peripheral seal around each of the blocks.

Another object of this invention is to provide a means for constructing a hollow wall which allows the mason or construction worker to lay the blocks without an additional supporting means, the present invention enabling the blocks to stand of their own accord.

A final object of this invention is to provide a building block interconnector which is inexpensive to manufacture, simple and easy to construct and use, and highly efficient in operation.

These, together with various ancillary features and objects of the invention, which will later become apparent as the following description proceeds are attained by the present invention a preferred embodiment of which is illustrated, by way of example only, in the accompanying drawings, wherein:

Figure 1 is a vertical perspective view illustrating a hollow wall together with the present invention applied thereto;

Figure 2 is a top plan view illustrating a portion of the instant invention applied to a pair of building blocks;

Figure 3 is a vertical end view, taken along the plane of section line 3—3 of Figure 2;

Figure 4 is a vertical side view taken along the plane of section line 4—4 of Figure 2;

Figure 5 is a fragmentary perspective view of a portion of the invention;

Figure 6 is a reduced top plan view illustrating a hollow wall construction having a partition extending therefrom and showing, in particular, the method of attaching the framing or reinforcing members of the present invention to a reinforcing member used in the partition wall.

2

Figure 7 is a fragmentary perspective view illustrating the reinforcing members for the partition wall as seen in Figure 6; and

Figure 8 is a fragmentary perspective view illustrating a further embodiment of the framing or reinforcing member as previously specifically illustrated in Figure 5.

Referring now more specifically to the accompanying drawings wherein like numerals designate similar parts throughout the various views, it will be noted that the numeral 10 designates a double or hollow wall construction, each wall consisting of a plurality of courses, as 12, 14 superposed one above the other, and supported by the foundation slab 16. Still more specifically, the courses consist of substantially rectangular building blocks 18, constructed of cement, stone, tile or other conventional building material.

The building block 18 has a peripherally extending groove 20 which includes upper and lower grooves 22, 24 and left and right grooves 26, 28, respectively, as seen in Figure 4.

The foundation block 16 is an elongated member preferably integrally cast and has a medially, longitudinally extending arcuate groove or gutter 30. At each of the upper outer surfaces of the block 16 is a longitudinally extending groove 31 similar in shape to the groove 20 in each of the building blocks 18.

Comprising the interconnecting members are the two ladder-shaped frames 32 and 34. The horizontal frame 32 consists of a pair of parallel side pieces 36 being rigidly secured in such a relationship by means of longitudinally spaced transversely disposed rung members 38. The vertical frame 34 is similar to the frame 32 but of a much reduced size depending upon the particular application, and consists of side pieces 40 and rungs 42. Both of these frames are preferably of a metallic or similar rigid material since the successful and efficient operation depends quite essentially on these members.

To construct a wall with these elements, the foundation block 16 is first laid. Side pieces 36 of horizontal frame 32 are then preferably compressibly placed in the grooves 31, as best seen in Figures 1 and 3, until the rungs 38 abut the block, thereby bridging the gutter 30.

A pair of courses, as 12 and 14, are then placed over the frame 32 by compressibly fitting the lower grooves 24, of these blocks on the now projecting portions of the side pieces 36. Between adjacent blocks in the same course, as 44 and 46, a frame, as 34, is emplaced having the side pieces 40 received in the left and right grooves 26 and 28 of the two blocks. The lower ends, as at 48,

of the vertical frame 34 embrace the horizontal frame 32, fitting on the outside of the side piece 36.

In a manner similar to that already discussed, another section of framing 32 is compressibly placed in the upper groove, as 22, of the first course, as 50, having the side pieces 36 received between the upper ends, as 52, of the frame 34. It is believed that it will be quite evident that the entire building wall may be constructed in the foregoing manner, adding an elongated section of ladder framing 32 between adjacent upper and lower courses and adding a vertical section of framing 34 between each of the adjacent blocks in a single course.

At the point of interception between the horizontal and vertical frames 32 and 34, respectively, the side pieces 36 and 40 may be welded or similarly secured whereby, in this manner, the entire wall is rigidly reinforced becoming, so to speak an integral construction. Although believed quite evident, it should be noted that the rungs 38 of the horizontal frame and the rungs 42 of the vertical frame prevent lateral displacement between the two walls thereby increasing the rigidity and reinforcement of the entire construction.

Referring now to Figure 6, there is illustrated the adaptation of the present invention to a partition wall 54 having embedded therein a reinforcing member 56. This reinforcing member, as seen in Figure 7, consists of an elongated strip of metal or similar rigid material, having struck-out portions 58 at spaced intervals therealong. Each of the struck-out portions 58 is preferably foldable so that the portion 58 is disposed at a right angular relationship relative to the strip 56. To further enhance the reinforcing qualities of the member 56, the struck-out portions are alternately folded in one direction and then in the other. This reinforcing member is adapted to the present invention since the struck-out portions 58 may be easily secured by welding or the like to the longitudinally extending frame member 32, as seen in Figure 6 at the numeral 60.

The framing members, either horizontal or vertical, 32 or 34, respectively, may alternatively be constructed in a manner such as that illustrated in Figure 8. Accordingly, one of the side pieces 62 has suitably spaced struck-out portions 64 foldable at right angles relative to the body of the side piece. The other side piece 66 is a solid member similar to that shown in the previous embodiment and acts as a solid member to which the foldable struck-out portion 64 may be connected, as seen at 68.

From the foregoing, the construction and operation of the invention, together with its many advantages will be readily apparent, and further explanation is believed to be unnecessary. However, since numerous modifications and changes will readily occur to those skilled in the art after a consideration of the foregoing specification and accompanying drawings, it is not desired to limit the invention to the exact construction shown and described and accordingly, all suitable modifications and equivalents may be resorted to, falling within the scope of the appended claims.

Having described the invention, what is claimed as new is:

1. A building structure comprising a pair of spaced parallel vertical walls each composed of superposed courses of substantially rectangular building blocks, each of said blocks having hori-

zontal grooves in their upper and lower edges and vertical grooves in their end edges, a longitudinal sealing and reinforcing bar partially received in the upper grooves of the blocks of each course, and also partially received in the lower grooves of an adjacent upper course, whereby adjacent courses of each wall will be interconnected, cross-bars permanently fixed to and joining the sealing and reinforcing bars of one wall to the sealing and reinforcing bars of the other wall, a vertical reinforcing and sealing bar in adjacent vertical grooves of adjacent blocks of each course, said vertical bars having ends overlapping and terminating against the outer faces of the longitudinal bars received in the upper and lower grooves in the blocks whose vertical grooves receive the vertical bars, and additional cross-bars terminally secured to the vertical bars of each wall and retaining the vertical bars parallel to each other and the vertical end edges of adjacent blocks of each course spaced apart.

2. A building structure comprising first and second spaced parallel vertical walls each composed of horizontally extending courses of substantially rectangular building blocks, each of said blocks having horizontal grooves in their upper and lower edges and vertical grooves in their end edges, a first horizontally disposed strip extending throughout the length of a course of said first wall and having a lower edge received in the upper groove in each block of the course of said first wall, said strip also including an upper edge received in the lower groove in each block of the course immediately above the course of said first wall receiving the lower edge of said strip, a second horizontal strip having a lower edge received in the upper groove of each block of a course of blocks of said second wall and having an upper edge received in the lower groove of each block of a course of said second wall immediately above the course of said second strip, horizontal cross-bars terminally fixed to the inner faces of said first and second strips and resting upon the upper edges of the courses of said walls whose blocks receive the lower edges of said strips, vertical strips received in the adjacent vertical grooves of adjacent blocks of each course and having ends overlapping and terminating against the outer faces of the strips received in the upper and lower grooves of the blocks whose vertical grooves receive said bars, and additional horizontal cross-bars terminally secured to the strips of adjacent courses of said first and second walls and spacing adjacent blocks of each course apart.

3. The combination of claim 2 wherein said first-mentioned cross-bars are struck from the horizontal strips of said first wall and include end flanges fixed to the horizontal strips of the other wall.
